UNITED STATES PATENT OFFICE.

FREEBORN F. RAYMOND, 2d, OF NEWTON, MASSACHUSETTS.

JACK FOR HEEL-NAILING MACHINES.

SPECIFICATION forming part of Letters Patent No. 480,741, dated August 16, 1892.

Application filed June 15, 1889. Serial No. 314,483. (No model.)

To all whom it may concern:

Be it known that I, FREEBORN F. RAYMOND, 2d, a citizen of the United States, and a resident of Newton, in the county of Middlesex 5 and State of Massachusetts, have invented a new and useful Improvement in Jacks for Heel-Nailing Machines, of which the following is a full, clear, and exact description, reference being had to the accompanying drawings, forming a part of this specification, in explaining its nature.

It is desirable for certain classes of work, especially for work known as "turned work," that the heel-seat be nailed and the heel attached upon the wooden last upon which the upper is lasted. The ordinary wooden last cannot well be used because the pintle-hole is not always bored straight or in proper position to receive the pin of the supporting jack, and also because the wood employed—generally maple—is not of sufficient strength to stand the pressure to which it is subjected in the nailing operation.

My invention relates to a wooden last fitted at the heel end to adapt it for the nailing of it and to the jack necessary for co-operating therewith.

Referring to the drawings, Figure 1 is a view in perspective of the last. Figs. 2 and 3 are views of the heel-plate. Fig. 4 is a view in side elevation of the upper part of the jack and the rear part of the last mounted thereon. Fig. 5 is a view in vertical section of the jack and last mounted thereon. Fig. 6 is a view of the form of jack which I prefer to use.

The last A is preferably made of wood and is what is known as the "fitting-last"—that is, it is the last upon which the upper is lasted. It has at its heel end a the bottom metal plate a', which is of the size of the bottom of the heel end of the last and which is preferably of considerable thickness, and which also has the cross rib or piece a² to strengthen it. This cross rib or bar a² is of course set into a recess of corresponding shape in the heel end of the last. The last also has extending inward from its top upon each side to the plate a² a recess a³, there being, of course, one recess on each side. These recesses are placed far enough from the back to not interfere with the proper support and

shaping of the back of the upper by the back of the last. The last as a whole therefore comprises the wooden body having a metal 55 plate a' at the heel and the side recesses a³.

The jack comprises a spindle, rod, or support B, which has vertical adjustment in the post b by means of the screw b' or in any other desired way, and it has formed upon its 60 upper end b² or attached thereto the arms b³ b⁴. These arms are of a size and length to fit the recesses a³ of the last in such a manner that the under surface of the plate a' at the end of the recesses shall rest upon the top b⁵ 65 of each arm. (See Fig. 5.) These arms may be integral with a base b⁶, as represented in Fig. 6, which is the construction I prefer to employ, or they may be separate and provided with a horizontal adjustment, as represented 7c in Fig. 5, in which case the lower end of each is shaped to slide in a dovetail recess c in the piece b², and they are made horizontally adjustable to and from each other in said base-piece by means of right and left screws c². 75 When the construction represented in Fig. 6 is employed, I prefer that the base-piece b⁶ have a hole b⁷ to fit the upper end b⁸ of the jack-spindle B. I prefer, also, that the jack have an adjustable bearing block or piece D, 8a located, preferably, between the two tops, although not necessarily so, and adapted to be lifted or depressed in relation to the end b⁵ and to form an additional support for the upper surface of the last, and I prefer that this 85 upper surface be armed with a metal plate d', secured by screws or otherwise to the last.

I have represented the support D as made adjustable by providing it with a threaded shank d², which screws into the threaded hole 90 d³ of the base b⁶. (See Fig. 6.)

Having thus fully described my invention, I claim and desire to secure by Letters Patent of the United States—

1. The improved last for use in connection 95 with a jack having the construction specified and in combination with said jack, comprising a body having its bottom at the heel end formed by the metal plate a' and also having the side recesses a³, substantially as 100 and for the purposes described.

2. The last A, the metal bottom plate a' for the heel end thereof, having the cross-bar a² upon its inner side, and the side recesses a³,

in combination with a supporting-jack, substantially as described.

3. The jack for use in connection with a last having the construction specified having 5 arms $b^3 b^4$, adapted to enter the side recesses a^3 of the last and to provide supports for the heel-plate a' thereof, combined with a vertically-adjustable support B, substantially as described.

10 4. The jack for use in connection with a last of the character specified, having arms $b^3 b^4$, and the support D, substantially as described.

15 5. A jack for use in connection with the last specified, having the arms $b^3 b^4$, the adjustable support D, and the adjustable support B, substantially as described.

6. The jack for use in connection with the

last of the character specified, having the arms $b^3 b^4$, horizontally adjustable to and from each other, substantially as described.

7. The jack for use in connection with a last of the character specified, having the arms $b^3 b^4$, the base b^6 , and the spindle-hole b^7 , combined with the support D, substantially as 25 described.

8. The combination of a jack having the arms $b^3 b^4$, with a last having the metal nail- 30 ing-plate a' at the heel end, and the side recesses a^3 to receive the said arms $b^3 b^4$, and the support B, substantially as described.

FREEBORN F. RAYMOND, 2d.
